(57) **CLAIM**

We claim the ornamental design for a mobile phone, as shown and described.

DESCRIPTION

FIG. 1 is a rear perspective view of a mobile phone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view thereof; and,

FIG. 9 is an exploded rear perspective view thereof.

The short dash-dash broken line in the figures represents unclaimed portions of the mobile phone and the dot-dash broken line in FIG. 9 defines the bounds of the claimed design; the broken lines form no part of the claimed design.
